UNITED STATES PATENT OFFICE.

CHARLES F. DATHAN, OF CHICAGO, ILLINOIS.

TORPEDO-NET FOR SHIPS.

1,347,363.

Specification of Letters Patent. Patented July 20, 1920.

Application filed December 7, 1918. Serial No. 265,808.

To all whom it may concern:

Be it known that I, CHARLES F. DATHAN, citizen of the United States of America, residing at Chicago, in the county of Cook and State of Illinois, have invented new and useful Improvements in Torpedo-Nets for Ships, of which the following is a specification.

This invention comprehends generally improvements in that class of invention known as "ships" and more particularly has reference to a torpedo net for ships.

It is the primary aim and object of the present invention to provide a device of the above character designed to surround that portion of the hull of a vessel beneath the water line to prevent torpedoes, mines, etcetera, from contacting with the hull of the vessel.

As an equally important object the present invention recites the provision of a device of the above mentioned character which is composed of a plurality of sections constructed desirably of reticulated means, such as woven wire, so that the shield will not interfere with the movement of the vessel in the water.

More particularly this invention includes a provision of improved supporting means for maintaining the sections of the shield in spaced relation to the sides of the hull when it is desired to employ the shield while said supporting means is also capable of being adjusted so as to draw the shield into close relation to the sides of the hull to permit of docking of the ship when desired.

As a further improvement this invention embraces the provision of improved means for connecting the sections of the shield to each other and to the supporting means; and to also provide improved means for swinging the supporting booms into such a position that the shield will be arranged in close relation to the hull of the ship.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illus-

tration a convenient and satisfactory embodiment of the invention. It is to be noted in this connection that minor changes in the construction and arrangement of parts may be made without departing from the principle of operation of the various parts. 55

The invention is clearly illustrated in the accompanying drawings, in which:—

Figure 1 is a side elevation of the invention.

Fig. 2 is a fragmental longitudinal sectional detail thereof. 65

Fig. 3 is a transverse section of the invention.

Fig. 4 is a top plan view of the invention, the device being arranged in a close arrangement to the side of the hull, and 70

Fig. 5 is an elevational detail illustrating the manner of connecting adjacent sections of the shield together.

Fig. 6 is a perspective detail of the outer extremity of one of the side booms. 75

Fig. 7 is a similar view of one of the bow or stern booms.

Similar characters of reference are employed in all of the above described views, 80 used to indicate corresponding parts.

Referring now, more particularly, to the accompanying drawings there is provided a ship 1 to the sides of whose hull at a point near the water line are connected at suitable intervals attaching plates 2 formed with outwardly projecting horizontally arranged ears 3 between which are arranged the inner ends of booms 4 pivoted for horizontal swinging movement between the ears by means of pintles 5. The outer ends of the booms 4 are formed with inwardly extending intersecting horizontally and vertically arranged slots 6 and 7 for a purpose that will presently appear. The elongated booms 8 have their inner ends pivoted through the instrumentality of pintles 9 for vertical swinging movement between spaced ears 10 which are projected from attaching plates 11 designed to be in turn secured to the bow and stern of the ship 1. These booms 8 are like the booms 4 formed at the outer ends with intersecting horizontally and vertically arranged slots 12 and 13. 95

With a view toward providing an improved means for protecting that portion of the hull beneath the water line a shield 100

60

90

95

100

105

14 is employed and consists generally of an intermediate section 15 and rear section 16 and a front section 17. These sections are desirably formed of reticulated material 5 such as woven wire, while suitable supporting and connecting cables 18 are trained through the adjacent ends of the sections 15 and 16 and 15 and 17 for connecting the sections together. The upper portions of 10 the cable 18 are trained through the vertical slots 7 in the outer ends of booms 4 while extreme upper terminals are connected to suitable posts 19 and in addition to connecting all sections of the shield serve 15 to brace the booms 4. Other cables 20 serve to connect the outer side edges of the sections 16 and 17 to each other, while the upper portions of the cables are trained through the vertical slots 13 and the ends 20 of the booms 8 and are finally connected to posts 21 carried by the bow and stern of the ship.

Coöperating with the cables 18 and 20 is another cable 22 which has one end connected 25 to the post 21 on the bow of the vessel and extends downwardly and is trained through the horizontal slot 6 in the adjacent boom 4. This cable is also trained through the upper edges of the sections 15 and 16 and through 30 the horizontal slots in the booms 4 and the rear boom 8 as it is arranged about the hull while the opposite end is extended upwardly and is anchored on the post 21 on the bow. By the provision of this cable 22 it is apparent 35 that subsequent to the raising of the rear cable 20 with a view to raising the rear boom 8 the ends of the cable 22 are pulled so as to draw the sections 15 and 16 in close relation with the adjacent portions of the hull to consequently permit the docking of the ship when desired. Coöperating with the front cable 20 is another cable 23 one end of 40 which is connected to a post 24 rearwardly of the forward post 19. This cable is trained 45 through a horizontal slot in the front booms 4 and in the front boom 8 and also through the upper edge of the section 17 of the shield preparatory to being connected at its opposite end to a post 25, which is disposed opposite to the post 24. When the ends of the 50 cable 23 are pulled, of course, subsequent to the pulling of the front cable 20 upwardly the section 17 will be drawn in close relation to the adjacent portion of the hull of the ship. In order to assure of the maintenance 55 of the sections of the shield in spaced relation to the keel as well as the bow and stern of the hull a relatively stiff curved or sinuous wire 26 is secured to the keel and the 60 stern and bow of the ship.

In use, when it is desired to arrange the shield in close relation with the sides of the hull of the ship 1, the front and rear cables 20 are pulled upwardly to raise the corresponding booms 8. Subsequent to this action

the ends of cables 22 are drawn inwardly and fastened about the posts 21 on the bow which draws the sections 15 and 16 toward the adjacent portions of the hull and also swings the booms 4 laterally so that they will be 70 held in proximity to the sides of the hull. Finally the ends of the cable 23 are tightened to draw the forward section 17 of the shield in close relation to the hull the cable being designed to slip through the slot in the ends 75 of the forward booms 4. When held in the position described the ship may be docked. To extend the shield it is only necessary to release the cables 22, 23 and 20, owing to the weight thereof the shield will swing downwardly and outwardly to assume the position as indicated in Figs. 1 and 3 of the drawings.

In view of the foregoing description a further detail description of the operation of the invention is entirely unnecessary. It is likewise believed that the advantages of the invention will be readily apparent.

Having thus fully described the invention what I claim and desire to secure by Letters Patent, is—

1. The combination with the hull of the ship of vertically swinging booms on the bow and stern thereof, laterally swinging booms on the sides of the hull, a sectional shield composed of a plurality of reticulated sections, connecting cables trained through the adjacent edges of the sections and through the ends of the laterally swinging booms and connecting to the hull at their terminals, other connecting cables trained 95 through the outer side edges of the end sections for connecting them together and also trained through the outer ends of the vertically swinging booms and having their upper terminals connected to the bow and stern 100 of the hull, and supporting cables trained through the ends of the booms and the upper edges of the sections of the shield and connected to the hull.

2. A device of the character described including a plurality of laterally swinging booms adapted to be connected to the sides of the hull of the ship and vertically swinging booms adapted to be connected to the bow and stern, the outer ends of the booms 115 being formed with intersecting horizontally and vertically arranged slots, a shield embodying extreme front and rear sections of reticulated material, connecting cables having their terminals secured to the opposite sides of the hull of the ship and being trained through the vertical slots of the laterally swinging booms and through the adjacent edges of the intermediate section and the front sections to the intermediate section 120 and the rear sections, other cables connected to the front section and the rear section for connecting the outer side edges of the said front and rear sections together and being trained through the vertical slots in the ver- 125 130

tically swinging booms and connected to the hull, a main supporting cable connected to the hull and trained for sliding movement through the horizontal slots in the lateral booms and through the horizontal slots in the vertically swinging booms for drawing the sections of the shield in close relation to

the sides of the hull subsequent to the raising of the front and rear connecting cables and the front and rear booms.

10

In testimony whereof I, CHARLES F. DATHAN, affix my signature.

CHARLES F. DATHAN.
